DESIGN FOR A TELEPHONE HOLDER

Herbert H. Webb, Grosse Pointe, Mich.

Application January 19, 1946, Serial No. 125,785

Term of patent 14 years

(Cl. D26—14)

To all whom it may concern:

Be it known that I, Herbert H. Webb, a citizen of the United States, residing at Grosse Pointe, in the county of Wayne and State of Michigan, have invented a new, original, and ornamental Design for a Telephone Holder, of which the following is a specification, reference being had therein to the accompanying drawing, forming a part thereof.

In the drawing:

What I claim is:

The ornamental design for a telephone holder as shown.

HERBERT H. WEBB.
